UNITED STATES PATENT OFFICE.

SAMUEL M. COFFMAN, OF KANSAS CITY, MISSOURI, ASSIGNOR TO THE BARBERS
ELECTRIC SPECIALTY COMPANY, A CORPORATION OF KANSAS.

DESIGN FOR A HAIR-CUTTING-MACHINE FRAME.

56,223.

Specification for Design. Patented Aug. 31, 1920.

Application filed May 17, 1918. Serial No. 235,195. Term of patent 14 years.

To all whom it may concern:

Be it known that I, SAMUEL M. COFFMAN, a citizen of the United States, residing at Kansas City, in the county of Jackson and State of Missouri, have invented a new, original, and ornamental Design for Hair-Cutting-Machine Frames, of which the following is a specification, reference being had to the accompanying drawing, in which:

Figure 1 is a side elevation of the frame of a hair cutting machine illustrating my new design.

Fig. 2 is a plan view thereof.

Fig. 3 is an end elevation thereof.

I claim:

The ornamental design for a hair cutting machine frame, as shown.

SAMUEL M. COFFMAN.
